CLAIM

The ornamental design for a cigar package, as shown and described.

DESCRIPTION

FIG. 1 is a top view of a cigar package of the present invention;

FIG. 2 is a bottom view thereof;

FIG. 3 is a right end view thereof;

FIG. 4 is a left end view thereof; and,

FIG. 5 is a side view thereof, the opposite side being a mirror image thereof.

The broken lines depict environment included to show the cigar package in a position of use and form no part of the claimed design.
